UNITED STATES PATENT OFFICE

GEORGE S. WITHAM, SR., OF HUDSON FALLS, NEW YORK

PAPER MAKING MACHINE

Application filed March 21, 1928. Serial No. 263,290.

It is a well known fact that the strong current of water running on the wire causes the fibres to position themselves in parallelism lengthwise of the wire. This condition not only creates a distinct grain in the subsequently formed web of paper, but reduces the transverse strength as well as the thickness of the paper.

Many attempts have heretofore been made to cross the fibres and thereby avoid the above objections, but such devices have been applied heretofore in the slice box in rear of the slice. In these prior constructions, the slices are usually lowered so that their lower edge is positioned in close proximity to the wire, thereby forming an exit opening extending entirely across the wire.

By reason of these slices, a pond of water is created. The speed of the water passing outwardly through the opening under the slice is regulated by the height of the pond in rear of the slice. This condition of course varies with different grades of paper being formed, as well as with different weights of paper that may be formed on the machine. The rate of flow of the stock must coincide with that of the speed of the wire on which the web is being formed. It will therefore be seen that all efforts heretofore made to cross the fibres at a point in rear of the slice are defeated because of the tendency of the fibres to straighten out lengthwise with the current of water gushing outwardly through the opening of the slice.

Among the several objects of my invention are to provide means for crossing the fibres at a point in advance of the slice, that is, after the pulp has passed the slice, so as to eliminate the influence that the action of the pond would have on the fibres, as well as eliminate the action of the water and fibres gushing outwardly through the narrow opening under the slice; to provide rotary agitating means for crossing the fibres; and to support and operate said agitating means in a manner to permit of vertical adjustment and variable speed of rotation thereof.

In the accompanying drawings, which illustrate one form of my invention, Figure 1 is a transverse sectional view through a slice

box showing the application of my invention.

Figure 2 is a vertical sectional view taken at right angles to Figure 1.

Figure 3 is a horizontal sectional view taken on the line 3—3 of Figure 2.

Referring to the accompanying drawings, I have shown my invention as applied to a paper making machine of the Fourdrinier type in which A indicates the slice box, B the Fourdrinier screen, C the table rolls, D—D the deckle straps, E—E the deckle plates, and F the transversely disposed slice. The slice F is mounted for vertical adjustment relative to the screen B to form an outlet opening 5 for the water and fibres.

Disposed directly in advance of the slice F above the screen and in cooperative relation therewith is my improved fibre agitating means G. This agitating means is supported by the deckle plates in a manner to permit the same to be vertically adjusted. To this end I provide a supporting frame 6 preferably of channel iron construction. This frame extends transversely between the deckle plates E and is guided in its vertical movements by guide bars 7—7.

The upper portions of the frame 6 extend outwardly so as to overhang the deckle plates E as at 8 and 9 respectively. Brackets 10 and 11 are attached to the projecting ends 8 and 9 respectively and are formed with vertically disposed threaded openings to receive the shanks 12 and 13 of adjusting screws 14 and 15 respectively, the lower ends of the screws contacting with the deckle plates E to support the agitating means in a position of vertical adjustment. Associated with each adjusting screw is a locking nut 16 which cooperates with the associated projection 8 or 9 to lock the screw against accidental turning.

Supported on the frame 6 is a plurality of vertically disposed shafts 17 having at their lower ends detachable agitators 18, which may be of any preferred construction. These shafts 17 are journaled in bearings 19 attached to the frame 6, and fixed to each shaft 17 above and below the frame 6 are stop collars 20—21 for retaining the shaft 17 against vertical movement relative to the

frame 6. The shafts 17 are adapted to be rotated at any desired speed by means of a variable speed motor 22 the agitators being thereby rotated in a horizontal plane. The motor 22 is mounted on a bracket 23 fixed to the projecting end 8 of the frame 6, so as to move up and down with the frame 6 when the latter is vertically adjusted. It will be noted that when the frame 6 is vertically adjusted the agitators 18 and the actuating means therefor will be correspondingly moved.

In order to rotate the shaft 17 from the motor 22, a driving shaft 24 is connected to the armature shaft of the motor by a coupling 25. The shaft 24 is journaled in bearings 25 located within a housing 26 fixed to the upper end of the frame 6 and provided with a movable cover 27. Fixed to the upper end 20 of each agitator shaft 17 is a worm gear 28 and secured to the shaft 24 is a plurality of worms 29 which mesh with the associated worm gears 28. The gears 28 and 29 are all located within the housing 26 and consequently the housing may be filled with grease for properly lubricating these gears.

From the foregoing it will be observed that the agitators 18 will be rotated by the motor 22 and the speed of rotation may be varied as desired, and also that these agitators may be vertically adjusted together with the motor 22, and thereby maintain the agitators in driving connection with the motor regardless of the vertical position of adjustment of the agitators relative to the wire.

In operation, as the water and fibres pass outwardly through the opening 5 under the slice F, the agitators 18 will stir and rotate the fibres so as to cause the latter to be crossed.

The crossed fibres will remain in this condition until the paper web is formed, and by crossing the fibres in this manner the thickness of the paper will necessarily be increased and the transverse tensile strength of the web will be correspondingly increased.

Obviously various details of the invention may be modified in their position and arrangement without in any way departing from the spirit of the invention, which is to be regarded as limited only by the scope of the appended claims.

What I claim is:

1. In a paper making machine, including a screen, the combination of a slice box having an outlet through which pulp will be discharged upon the screen, a plurality of pulp agitating devices located above the screen and in cooperative relation therewith in advance of the opening and supported on vertical axes for rotary movements in a horizontal plane, and means for rotating said devices.

2. In a paper making machine, including a screen, the combination of a slice box hav-

ing an outlet through which pulp will be discharged upon the screen, a frame extending across the box and supported thereon for vertical adjustments, a plurality of horizontally movable pulp agitating devices located above the screen and in cooperative relation therewith, said agitating devices being carried by the frame and movable therewith, and actuating means for said devices supported by and movable with said frame.

3. In a paper making machine, including a screen, the combination of a slice box having an outlet, a frame extending across the box adjacent the outlet and supported on said box for vertical adjustments, a plurality of shafts journaled on the frame for rotation about vertical axes above the screen, a plurality of pulp agitating devices respectively fixed to the lower ends of the shafts and in cooperative relation with the screen, a motor supported by and movable with said frame, and driving connections between the motor and said shafts.

4. In a paper making machine, the combination of a slice box having an outlet, a frame extending across the box adjacent the outlet and supported on said box for vertical adjustments, a plurality of shafts journaled on the frame for rotation about vertical axes, a plurality of pulp agitating devices fixed to the lower ends of the respective shafts, a motor supported by and movable with said frame, and driving connections between the motor and said shafts including a driving shaft and gear couplings between the driving shaft and the vertical shafts, and a lubricant containing housing for the gear couplings supported on said frame.

5. In a paper making machine including a screen, the combination with a slice box adapted to discharge pulp upon the screen and including a slice; of a vertically adjustable frame mounted on said box; pulp agitating means carried by the frame and rotatable in a horizontal plane above the screen and in cooperative relation therewith in advance of the slice; a motor mounted on the frame; and driving connections between the motor and the agitating means carried by the frame.

6. In a paper making machine, the combination of a Fourdrinier screen adapted to receive pulp for the formation of a paper web, a movable agitating device located above the screen and in cooperative relation therewith, and means mounting said agitating means for movements in a substantially horizontal plane in contact with the pulp on said screen.

7. In a paper making machine, the combination of a Fourdrinier screen adapted to receive pulp for the formation of a paper web, a rotatable agitating device located above the screen and in cooperative relation therewith, and means mounting said agitating means for rotary movements in a substan-

tially horizontal plane in contact with the pulp on said screen.

8. In a paper making machine including a screen, the combination of a slice box having 5 an outlet arranged to discharge pulp from said box on to said screen, movable pulp agitating means, and means mounting said agitating means for movements in a horizontal plane above the screen and in contact with 10 the pulp thereon in advance of said outlet.

9. In a paper making machine including a screen, the combination of a slice box having an outlet arranged to discharge pulp from 15 said box on to said screen, rotatable pulp agitating means, and means mounting said agitating means for rotation in a horizontal plane above the screen and in contact with the pulp thereon in advance of said outlet.

In testimony whereof, I have hereunto 20 subscribed my name.
